JAMES HAVERLY AND CHARLES A. TIBITTS, OF LA PORTE, INDIANA.

Letters Patent No. 82,405, dated September 22, 1868.

IMPROVED THILL-COUPING.

The Schedule referred to in these Letters Patent and making part of the same.

TO ALL WHOM IT MAY CONCERN:

Be it known that we, JAMES HAVERLY and CHARLES A. TIBITTS, of the city of La Porte, in the county of La Porte, and State of Indiana, have invented a new and useful Improvement in Thills and Pole-Shackles; and we do hereby declare that the following is a full, clear, and exact description of the same, reference being had to the annexed drawings, making part of this specification, in which—

Figure 1 is a side elevation.

Figure 2 is a side sectional elevation.

Figure 3 is a top view, and

Figure 4 is an end view.

Our improvement relates to that class of shackles which for convenience drop into the box and fasten themselves, dispensing with the old style of bolts and nuts, and the points on which we have made our improvements on former shackles will appear from the claims hereinafter to be set forth.

In the drawings, A is the clasp, which is fastened around the axle, and tightened by means of the nuts C C. B is the oval double-toothed box, which is open at the top, into which the bolt D drops, which bolt D is at the base of the arm E. The arm E may be made in any shape or any length desired, and to which arm E, the thills or pole is fastened; the box B being slotted so as to allow the arm E to be elevated or lowered at pleasure, and to firmly hold the thills or pole from slipping either way. The clasp on the lower side of the butt end of the arm E, which passes around the outside of the box B, holds the bolt D and arm E firmly in their place, and keeps the thills or pole from rattling, and also the bolt D from bouncing out of the box B. There being a more even wear on the bolt D, it is less liable to become loose and rattle than any other style of shackle, but in case it should become loose and rattle, the noise is easily obviated by putting in a small piece of rubber in the middle and back side of the box B. The thills or pole may be taken off or changed instantly, by elevating the same, so as to lift the bolt D out of or drop the same into the box B, saving time and trouble, and doing away entirely with bolts and nuts.

What we claim as our invention, and desire to secure by Letters Patent, is—

1. The construction of the clasp A with its box B attached thereto, substantially as shown and described.
2. The construction of the arm E, and the arrangement thereof with reference to the box B, substantially as set forth.

In testimony whereof, we have signed our names to this specification in the presence of two subscribing witnesses.
